UNITED STATES PATENT OFFICE.

JULIUS WAGNER, OF READING, PENNSYLVANIA.

HARNESS-HOOK.

SPECIFICATION forming part of Letters Patent No. 310,235, dated January 6, 1885.

Application filed September 10, 1884. (No model.)

To all whom it may concern:

Be it known that I, JULIUS WAGNER, a citizen of the United States, residing at the city of Reading, county of Berks, State of Pennsylvania, have invented a new and useful Improvement in Check-Hooks, of which the following is a specification.

This improvement relates to all styles of harness-saddle terrets, and is applicable to both the check-hooks and ring-terrets of the same, I reserving the latter for a future application.

The object of the improvement is to give ease to the harnessed animal and a cheap construction of the hook. This object is attained in the use of the improvement shown in the accompanying drawings, in which similar letters indicate similar parts.

Figure 1 is an elevation of a check-hook of the usual style having my prior improvement thereon. Fig. 2 is an elevation of the same check-hook with the subsequent and completed improvement attached thereto. Fig. 3 is a detail of an alternative roller.

A represents the lower arm of the check-hook; A', the upper arm or keeper; A², the check-hook guard; A³, seat for roller-base; B, the bolt for securing to harness-saddle; B', screw-thread; B², nut; C, spindle cast or formed integral with the body of the check-hook; D, roller or anti-friction device; H, alternative roller in halves; I, rings for securing the halved roller in place.

The effect of the ordinary check-hook attachment upon the animal is restrictive, and each movement of the animal's head to the right or left is made by an effort first exerted upon the bridle-rein to move or slide it upon the check-hook, which, being small in diameter, usually kinks the rein, so that considerable strain is thrown upon the animal's neck before movement is to any great extent possible.

The improved terret check-hook permits instantaneou, free, and unlimited movement of the animal's head on a horizontal plane without any strain being thrown upon the same.

The construction of the terrets, both ring and check-hook, is as follows: At about the point of attachment of the bridle-rein, or the frictional point of the lines within the interior surface of the rings, the body of the ring

or check-hook terrets is compressed or reduced to the form of a spindle of uniform diameter, 55 said spindle being so arranged relative to the inner surface of the ring or hook terrets that the anti-friction rollers shall about preserve the contour of the interior surfaces of the same. Seats A³ are formed to give vertical 6c support to and a wearing-base for the rollers. After tumbling and annealing the check-hooks they are placed in suitably-prepared flasks and the rollers D cast thereon, thus making a cheap and permanent attachment of the anti- 65 friction rollers to the check-hooks.

The rollers may be molded upon the check-hooks in celluloid, rubber, or equivalent material, and subsequently hardened or vulcanized; or they may be constructed in halves 70 and secured in place upon the spindles by rings I; but I prefer to cast them of metal directly upon the spindles formed upon the check-hooks.

I am aware that I am not the first to make 75 use of anti-friction devices in combination with terret check-hooks; but I believe that my mode of constructing the same is a novel, useful, and cheap and effective mode of manufacturing the same. I make no claim to the 80 rollers *per se*, but to my placing of the same upon the spindles in the manner described, and thus saving machine-work upon the same.

Having described my improvement and shown its use and advantages, I desire to secure by Letters Patent the following claims 85 thereon:

1. As an improved article of manufacture, a terret-hook for a harness-saddle, provided with keeper A', guard A², spindle C, and seats 90 A³, cast or formed integral with the body of said hook, in combination with the harness-saddle by the usual bolt and nut, B B², substantially as and for the purpose set forth.

2. As an improved article of manufacture, 95 a terret-hook for a harness-saddle, provided with keeper A', guard A², spindle C, and seat A³, cast or formed integral with the body of said hook, in combination with an anti-friction roller, D, substantially as and for the purpose set forth.

JULIUS WAGNER.

Witnesses:

THOMAS P. KINSEY,
F. PIERCE HUMMEL.
